CHILD'S CAR SEAT

Richard E. Cone II, 249 Bowman Drive, Kent, Ohio
44240, and Leo F. Wildgen, 9431 10th Ave. S., Minneapolis, Minn. 55420

Filed July 14, 1975, Ser. No. 595,696

Term of patent 14 years

Int. Cl. D6—01

U.S. Cl. D6—9

FIG. 1

—FIG. 2

— FIG. 3

FIG. 4

FIG. 5

FIG. 1 is a front view showing a child's car seat design of our invention;

FIG. 2 is a right side view thereof;

FIG. 3 is a back view thereof;

FIG. 4 is a top plan view thereof; and

FIG. 5 is a bottom view thereof.

The side of the seat not shown in the drawing is a mere image of the side shown.

We claim:

The ornamental design for a child's car seat, as shown and described.
